(57) **CLAIM**

I claim the ornamental design for a collapsible table frame, as shown.

DESCRIPTION

FIG. 1 is a perspective view of a collapsible table frame showing the ornamental design of the invention.

FIG. 2 is a perspective view of the collapsed table frame showing the ornamental design of the invention.

FIG. 3 is a perspective view of a partially collapsed table frame showing the ornamental design of the invention.

FIG. 4 is a perspective view from the front of the ornamental design of the collapsible table frame of the invention.

FIG. 5 is a perspective view from the back of the ornamental design of the collapsible table frame of the invention.

FIG. 6 is a side view of the ornamental design of the collapsible table frame of the invention.

FIG. 7 is a perspective view from the top of the ornamental design of the collapsible table frame of the invention; and, FIG. 8 is a perspective view from the bottom of the ornamental design of the collapsible table frame of the invention.

The broken lines are for environmental purposes only and form no part of the claimed design.
